UNITED STATES PATENT OFFICE.

KINGSTON FORBES, OF FLINT, MICHIGAN.

SPARK-PLUG FOR INTERNAL-COMBUSTION ENGINES.

1,247,102.

Specification of Letters Patent. Patented Nov. 20, 1917.

Application filed August 23, 1916. Serial No. 116,515.

To all whom it may concern:

Be it known that I, KINGSTON FORBES, a citizen of the United States, residing at Flint, in the county of Genesee and State of 5 Michigan, have invented certain new and useful Improvements in Spark-Plugs for Internal-Combustion Engines, of which the following is a specification, reference being had to the accompanying drawings.

10 This invention relates to an improved spark plug for internal combustion engines and has for its primary object to provide improved means for detachably connecting the outer electrode to the plug shell so as to 15 afford ready access to the parts of the plug for the purpose of removing carbon deposits.

It is another important object of the invention to provide a detachable electrode which is so constructed and mounted in the 20 plug shell that the same will be held against all possibility of accidental displacement by the wall of the engine cylinder in which the plug is threaded.

It is a further general object of my invention to simplify and improve the construction of engine spark plugs and increase the 25 operating efficiency and serviceability thereof in practical use, though without increasing the manufacturing cost of the plug to 30 any material extent.

With the above and other objects in view, my invention consists in the novel features 35 of construction, combination and arrangement of parts to be hereinafter more fully described, claimed and illustrated in the accompanying drawing, in which,

Figure 1 is a vertical sectional view of a 40 spark plug, illustrating the preferred embodiment of my invention and showing the same mounted in a cylinder wall;

Fig. 2 is a horizontal section taken on the line 2—2 of Fig. 1;

Fig. 3 is a side elevation of a part of the 45 spark plug shell, the electrode being detached therefrom; and

Fig. 4 is a detail perspective view of the detachable electrode.

Referring in detail to the drawing, 5 designates the core of porcelain or other 50 suitable material constituting the body of the plug, and 6 the metallic shell within which the porcelain core is fitted and permanently fixed or secured in any approved manner. The reduced stem of the shell 6 has 55 an exteriorly threaded portion 7 for engage-

ment in the threaded opening of the cylinder wall shown at C. The electrode 8 receiving the positive current, extends centrally through the porcelain body 5 and is secured therein by any preferred means, the lower 60 end of said electrode projecting below the lower end face of the plug. As thus far described, the spark plug is quite common in the art, and has been generally adopted in preference to the sectional spark plug which, though it admits of better and more thorough cleaning, is impractical in use owing to the fact that it is almost impossible to make the plug gas-tight. On the other hand, 65 a plug of the latest improved type having 70 the inseparably connected porcelain body and outer metal shell is hard to clean, as the outer electrode is permanently connected to the shell so that access to the various crevices within which carbon finds lodgment cannot 75 be readily obtained.

It is, therefore, the primary purpose of the present invention to devise an improved 80 detachable outer electrode which may be very easily and quickly disconnected from the spark plug shell or applied thereto, whereby the above noted objection to the inseparable plug construction is obviated. To this end, I provide longitudinally extending grooves 9 at diametrically opposite 85 points in the periphery of the shell 6, said grooves extending through the threaded section 7 of said shell. An opening 10 is formed in the shell wall at the inner end of each of these grooves or channels 9. 90

The detachable electrode 11 is of U-shaped form, the parallel end portions 12 thereof being sufficiently resilient to enable the same to be sprung apart or away from each other. The extremities of the said portions 12 of 95 the electrode are angularly disposed to provide inwardly projecting lugs 13. In applying the detachable electrode to the spark plug shell, the end portions 12 are sprung apart sufficiently to enable the lugs 13 to be 100 engaged in the grooves or channels 9, and said electrode is then forced longitudinally upon the shell until the lugs snap into the openings 10. The grooves 9 are sufficiently deep to entirely receive the end portions 12 of the electrode. The intermediate portion 105 of the electrode 11 extends diametrically across the bottom of the shell in spaced relation thereto and in spaced relation to the lower end of the electrode 8, the space be- 110

tween said electrodes constituting the spark gap.

From the foregoing description, taken in connection with the accompanying drawing, 5 the construction and manner of assembling the several parts of my improved spark plug will be clearly and fully understood. It is to be particularly observed that when the spark plug is threaded in place within the 10 wall of the cylinder C, the end portions 12 are disposed within the opening in the cylinder wall so that they are positively held within the grooves 9 against displacement. When it is desired to clean the plug, the 15 same is removed from the cylinder wall and the end portions 12 of the electrode 11 then sprung outwardly so as to disengage the lugs 13 from the openings 10. The electrode 11 may then be shifted longitudinally and entirely disconnected from the spark plug. 20 Access may now be readily had to the various crevices between the porcelain body and the shell of the plug with a knife or other suitable tool and such carbon as has been 25 deposited therein removed. Thus, the serviceability and efficiency of the plug in practical operation may be maintained, and the thorough cleaning of the plug very easily and quickly accomplished. It is, of course, 30 apparent that the illustrated plug construction is simply indicative of that general type of inseparable spark plug to which my invention is particularly applicable, and it is to be understood that the detachable electrode may as readily be employed in connection with various other plug constructions of this general type. The device is also susceptible of considerable modification 35 in the form, construction and arrangement 40 of its several features and I, therefore, reserve the privilege of adopting all such legitimate changes as may be fairly embodied within the spirit and scope of the invention as claimed.

45 Having thus fully described my invention, what I desire to claim and secure by Letters Patent is:—

1. The combination with a spark plug shell, of an electrode having spaced, resilient portions to clampingly engage the exterior of the shell at diametrically opposite points, each spaced portion of the electrode being provided with terminal means for interlocking connection with the shell.

55 2. The combination with a spark plug shell having diametrically opposed openings in its wall, of an electrode having spaced, resilient portions to clampingly engage the exterior of the shell at diametrically opposite points, and said spaced portions having terminal means for engagement through said openings.

65 3. The combination with a spark plug shell having openings at diametrically opposite points in its wall, of an electrode con-

sisting of a resilient, metal rod bent to provide spaced, parallel portions adapted to clampingly engage the exterior of the shell, each of said parallel portions having an inwardly projecting terminal lug formed 70 thereon for engagement through one of the openings in the shell.

4. The combination with a spark plug shell, of an electrode consisting of a U-shaped rod having resilient end portions 75 adapted to clampingly engage the exterior of the spark plug shell at diametrically opposite points, the terminals of the electrode being wholly disposed within the opening in the cylinder wall and held by the wall and 80 the spark plug shell against relative movement.

5. As an improved article of manufacture, a spark plug electrode formed from a resilient rod bent to provide spaced, yieldable 85 portions adapted for detachable clamping engagement against opposite sides of the spark plug shell, each of said portions having an inwardly projecting terminal lug for locking engagement with the shell. 90

6. The combination with a spark plug having an insulating body provided with an electrode and a metal shell within which said body is permanently secured; of a complementary electrode having spaced resilient 95 portions for detachable clamping engagement with the shell of the spark plug.

7. The combination with a spark plug having an insulating body provided with an electrode and a metal shell within which said body is permanently secured, of a complementary electrode of substantially U-shaped form, the spark plug shell being provided upon diametrically opposite sides with longitudinal grooves to receive the terminal 100 portions of said electrode, said portions of the electrode being held within the grooves 105 against displacement by the wall of the engine cylinder.

8. The combination with a spark plug 110 having an insulating body provided with an electrode and a metal shell within which said body is permanently secured, of a complementary electrode of substantially U-shaped form having spaced, parallel, resilient portions, the spark plug shell being provided upon diametrically opposite sides with longitudinal grooves in which the yieldable portions of the electrode for clamping engagement, said yieldable portions of the 115 electrode being held within said grooves by the wall of the engine cylinder.

9. The combination with a spark plug having an insulating body provided with an electrode and a metal shell within which said body is permanently secured, of a complementary, detachable electrode of substantially U-shaped form having spaced, parallel, resilient portions provided with inwardly projecting terminal lugs, the spark plug shell 120

being provided with longitudinal grooves on diametrically opposite sides and an opening at the inner end of each of said grooves to receive the terminal lugs on said electrode,
5 the terminal lugs of the electrode being held within said openings by the wall of the engine cylinder.

In testimony whereof I hereunto affix my signature in the presence of two witnesses.

KINGSTON FORBES.
